Primary Examiner — Ian Simmons*Assistant Examiner* — Mark Cavanna*(74) Attorney, Agent, or Firm* — Neal O. Willmann(57) **CLAIM**

The ornamental design for the leg support, as shown and described.

DESCRIPTION

FIG. 1 is a perspective view of a leg support showing our new design;

FIG. 2 is a perspective view from the back side thereof;

FIG. 3 is a front elevation view thereof;

FIG. 4 is a back side elevation view;

FIG. 5 is a right side elevation view thereof; the left side being a mirror image.

FIG. 6 is a top plan view thereof; and,

FIG. 7 is a bottom plan view thereof.

The partial leg and foot depicted in broken line are shown for illustrative purposes only and form no part of the claimed design.

1 Claim, 7 Drawing Sheets(56)
